Application November 16, 1944, Serial No. 563,713

11 Claims. (Cl. 178—44)

1

The present invention relates to high-frequency impedance-matching devices and, particularly, to such devices of a type adapted for connection between and for matching a pair of impedances having any values within a substantial range of magnitude and phase.

It is well known that maximum power transfer is effected in an electrical circuit when the impedance of a power source is matched with the impedance of the load which is coupled to the source and to which the power is supplied. In electrical circuits operating at high frequency, for example in high-frequency wave-signal circuits, the impedances encountered and required to be matched are complex so that a satisfactory result necessitates a matching of the resistance components and a cancellation of the reactance components of the impedances.

Transmission lines of either fixed or adjustable lengths have heretofore been widely used as impedance-matching devices, especially in high-frequency wave-signal circuits. A transmission line when so used exhibits the properties of an impedance transformer in that it is able to transform the value of an impedance coupled to one end of the line to a different value of impedance at its other end. The maximum ratio of impedance transformation varies with the ratio between the characteristic impedance of the line and the value of the impedance to be transformed, but both the actual ratio of the impedance transformation and the magnitude and nature of the reactance components after transformation vary with the effective electrical length of the transmission line. The use of an open or balanced type of transmission line for this purpose requires an adjustment both of the line length and line characteristic impedance where an impedance balance at several operating frequencies is required. This is because both the magnitudes and phase angles of the impedances to be matched and the electrical length of the line all vary with frequency.

It has been proposed that a coaxial transmission line one wave length or more long be employed for impedance matching, the line having a characteristic impedance equal to the value of impedance of one or both of the terminal impedances and being provided with two quarter-wave sliders which surround the inner conductor of the line and are independently adjustable axially therealong. These sliders modify the characteristic impedance of the line over the length of each slider and effect, over a range of impedances, a matching of the resistance com-

2

ponents and a cancellation of the reactance components of two impedances coupled to individual ends of the line. This impedance-matching device when once properly adjusted to provide an impedance match at one operating frequency may not maintain even an approximate impedance match over more than a small range of operating frequencies so that the device may be said to be critical of frequency. The reason for this is that the change of phase through the line with change of frequency becomes more severe as the line length increases, there being a cumulative phase shift for the reflected wave-signal energy which is produced at a multitude of points along the length of the device described. It is desirable in many applications that an impedance-matching device provide an exact impedance match at one frequency and that a closely approximate impedance match be maintained without further adjustment over a substantial range of operating frequencies. Additionally, it is frequently desirable that an impedance-matching device of this type have a physical size appreciably smaller than is possible with the device described.

It is an object of the present invention, therefore, to provide a new and improved high-frequency impedance-matching device which avoids one or more of the disadvantages of prior devices of this type.

It is an additional object of the invention to provide a new and improved high-frequency impedance-matching device having minimum physical size, one of simple yet sturdy construction, and one which is characterized by ease and facility of adjustment where an impedance match is required between complex impedances having substantial differences of magnitude and phase.

It is a further object of the invention to provide a new and improved high-frequency impedance-matching device which is not as critical of adjustment as has heretofore been the case with prior devices of this type and one which, when adjusted to provide an exact impedance match at one operating frequency, maintains a reasonably close approximate impedance match over a wide range of operating frequencies.

In accordance with the invention, a high-frequency impedance-matching device adapted for connection between and for matching at a given frequency a pair of impedances having any values within a predetermined range of magnitude and phase comprises a plural-conductor transmission line adapted to be connected between the impedances and having a predeter-

mined electrical length less than one wave length at the aforementioned given frequency and a predetermined characteristic impedance differing in one sense from the geometric mean of the pair of impedances. The device includes a plurality of members positioned between the conductors of the line and independently adjustably movable axially therealong. Each of the adjustable members has at the given frequency a predetermined effective electrical length substantially less than one-half the length of the line and has its shape and material so selected as to cause the characteristic impedance of the line over the lengths of the members to differ from the geometric mean of the aforesaid impedances in opposite sense from the sense in which the line differs therefrom, and by such magnitude as to enable the transmission line for an adjusted position of the members to match the resistance components and to cancel the reactance components of the aforesaid pair of impedances.

The present invention is related to that disclosed and claimed in applicant's copending application entitled Wave-signal transmission line, Serial No. 563,714, filed November 16, 1944, and assigned to the same assignee as the present invention. Whereas the transmission line of the copending application utilizes a member of magnetic material movable axially along the line to effect an adjustment of the line terminal impedance, the impedance-matching device of the present invention utilizes two members of conductive, dielectric or magnetic material axially independently movable along a quarter-wave line for purposes of matching, over a range of values of magnitude and phase, two impedances which are coupled to individual ends of the line. The present invention is also related to the device of applicant's copending application entitled Wave-signal tuning device, Serial No. 563,712, filed November 16, 1944, and assigned to the same assignee as the present application. In the last-mentioned copending application, a member of conductive, dielectric or magnetic material, or a combination of such materials, is axially movable along a transmission line having an electrical length of an odd number of quarter-wave lengths and short-circuited at its remote end to provide a resonant line adjustable to resonance at any frequency in a range of operating frequencies.

For a better understanding of the present invention, together with other and further objects thereof, reference is had to the following description taken in connection with the accompanying drawings, and its scope will be pointed out in the appended claims.

In the drawings, Fig. 1 is a longitudinal sectional view of a high-frequency impedance-matching device embodying the present invention; Fig. 2 is a diagrammatic representation of the device of Fig. 1; Fig. 3 is a sectional view of an embodiment of the invention which is useful for matching one impedance to a pair of parallel impedances; and Fig. 4 is an impedance chart for the devices of Figs. 1 and 3 and is used to demonstrate their capabilities.

Referring now more particularly to the drawings, the device illustrated in Fig. 1 and shown diagrammatically in Fig. 2 comprises a high-frequency impedance-matching device which is adapted for connection between, and for matching at a given frequency, a pair of unequal impedances designated Z_1 and Z_2 having any values within a substantial range of magnitude and phase. This device comprises a plural-conductor

coaxial transmission line including a hollow outer conductor 11 and an inner conductor 12 maintained in coaxial relationship by spaced insulating discs 13, 13. The transmission line 11, 12 has a characteristic impedance Z_0' differing in a given sense from, for example an impedance either higher or lower than, the geometric mean of the terminal impedances Z_1 , Z_2 and an electrical length less than one wave length at the aforementioned given frequency. Minimum physical size is attained when the transmission line has an electrical length equal to one-quarter wave length. When the ratio of the terminal impedances Z_1 to Z_2 , or vice versa, is relatively large, the transmission line 11, 12 preferably has an effective electrical length equal either to one-quarter wave length or to three-quarters wave length since it then is enabled to provide an optimum ratio of impedance transformation between its terminal ends. The discs 13, 13 are held in position by suitable means such as screws 14. Terminals 17, 17 and 18, 18 are provided at opposite extremities of the conductors 11 and 12 to permit the impedances Z_1 , Z_2 which are to be matched to be connected in circuit with the device.

The impedance-matching device also includes a plurality of members 15, 16 positioned between the conductors 11 and 12 and independently adjustably movable axially along the conductors. Each of the adjustable members 15 and 16 has at the aforementioned given frequency a predetermined effective electrical length substantially less than one-half the length of the line 11, 12, a preferred physical length for optimum range of control being one-quarter the line length but not exceeding a physical length which provides an effective electrical length of one-quarter wave length. The members 15, 16 have their shape and material so selected as to cause the characteristic impedance Z_0'' of the line 11, 12 over the lengths of the members 15, 16 to differ from the geometric mean of the terminal impedances Z_1 , Z_2 , though in opposite sense from the sense in which the line 11, 12 differs therefrom, and by such magnitude as to enable the transmission line for an adjusted position of the members 15, 16 to match the resistance components and to cancel the reactance components of the terminal impedances Z_1 and Z_2 . Specifically, the members 15 and 16 may be of conductive, dielectric, or magnetic materials, or a combination of these materials and, for a coaxial transmission line, are preferably of circular cross section. The adjustable members 15 and 16 are movable by the insertion of a suitable tool, through a slot 40 in the outer conductor 11, into engagement with screws 25 which are loosened during adjustment of members 15 and 16 but are tightened thereafter to engage the inner conductor 12 for the purpose of maintaining the members 15, 16 in adjusted position.

A brief discussion of the design of the impedance-matching device to provide proper matching for a pair of unequal impedances Z_1 and Z_2 follows. When the members 15 and 16 are of conductive or dielectric materials, the outer diameter of the inner conductor 12 and the inner diameter of the outer conductor 11 are so proportioned that the characteristic impedance Z_0' of the line is substantially greater than the geometric mean impedance of the terminal impedances Z_1 and Z_2 . When the members 15 and 16 are of conductive material and electrically engage the inner conductor 12, the outer diameters thereof are proportioned with relation to the in-

ner diameter of the conductor 11 so that the characteristic impedance Z_0'' of the line over the lengths of the members 15 and 16 is substantially less than the aforementioned geometric mean value. This applies also in the event the members 15 and 16 are of conductive material but electrically engage only the outer conductor 11, there being the difference in this case that the inner diameter of the members 15 and 16 are proportioned with relation to the diameter of the conductor 12 to effect the reduction of characteristic impedance last mentioned. If, on the other hand, the members 15 and 16 are of dielectric material, the desired reduction of line characteristic impedance over the lengths of the members is effected by a choice of the dielectric constant of the material used.

In the alternative case where the members 15 and 16 are of material having an effective predominant magnetic characteristic, the transmission line 11, 12 is proportioned to have a characteristic impedance Z_0' substantially less than the geometric mean impedance of Z_1 and Z_2 and the effective coefficient of magnetic permeability of the material of members 15 and 16 is so selected with relation to the effective dielectric constant of the members that the characteristic impedance Z_0'' of the line 11, 12 is substantially greater than the geometric mean impedance of Z_1 and Z_2 over the lengths of these members. The adjustable members, having an effective electrical length of approximately one-fourth the length of the line 11, 12 and thus a range of movement equal at least to their own length, provide ample flexibility for matching unequal impedances Z_1 and Z_2 over a wide range of impedance ratios.

It will be observed that the matching device is, in effect, a transmission line consisting of a series of transmission lines of different characteristic impedances Z_0' and Z_0'' , the relative lengths of those line portions having the characteristic impedance Z_0' being adjustable. It is therefore apparent that the characteristic impedance of any portion of the matching device may be determined by conventional formulas applicable to transmission lines, the formula for an air-dielectric coaxial line being given by the relation:

$$Z_0 = 138 \log_{10} \frac{D}{d} \quad (1)$$

where

D =the inner diameter of the outer conductor of the line portion under consideration, and d =the outer diameter of the inner conductor of the line portion considered.

For those line portions having adjustable members of dielectric material, the characteristic impedance given by Equation 1 must be multiplied by the reciprocal of the square root of the effective dielectric constant of the member, the effective dielectric constant taking into account any air gaps between the adjustable member and either or both of the conductors 11 and 12. Similarly, where the adjustable member is of magnetic material, the characteristic impedance given by Equation 1 must be multiplied by the square root of the effective magnetic permeability and divided by the square root of the effective dielectric constant of the member.

In order to match most complex impedances Z_1 , Z_2 over a substantial range of impedance ratios, two independent adjustments of the impedance-matching device are required. The adjustable members 15 and 16 provide this matching feature.

Considering now the operation of the device shown schematically in Figs. 1 and 2, with impedances Z_1 and Z_2 connected thereto, the terminal impedances are matched by sliding the adjustable members 15 and 16 so as to vary the distance B , or the distance A , Fig. 2, or both the distances A and B . The adjustments in this regard are somewhat similar to those required to balance resistance and reactance components of an unknown impedance in an alternating current Wheatstone bridge.

For the range of impedance adjustment to include the geometric mean of the terminal impedances Z_1 and Z_2 , the following relation should be fulfilled:

$$\sqrt{\frac{L}{C}} = \sqrt{Z_1 Z_2} \quad (2)$$

where

20 L =the total inductance of the line conductors 11 and 12 including the inductance of the members 15 and 16,

25 C =the total capacitance between the line conductors 11 and 12 including the members 15 and 16.

The maximum range of adjustment, insofar as the length of the members 15, 16 is concerned, is attained by the preferred length described above; namely, a physical length for each member equal to one-quarter the physical length of the line 11, 12 although the effective electrical length of the member, which will be greater than its physical length where the member is of dielectric or magnetic material, should not exceed one-quarter wave length of the translated electromagnetic-wave signal.

The maximum range of adjustment about the geometric mean of the terminal impedances Z_1 and Z_2 , insofar as the characteristic impedances Z_0' and Z_0'' are concerned, is attained when the following relation is fulfilled:

$$\sqrt{Z_0' Z_0''} = \sqrt{Z_1 Z_2} \quad (3)$$

45 For a length l of the line 11, 12 equal to or less than one-half wave length λ of the translated wave signal and for a value of K , defined below, less than unity, the following relation gives the approximate value of the reflection coefficient r that can be introduced or cancelled:

$$r = \frac{K}{2} \left(\frac{\pi l}{\lambda} \right)^2 \quad (4)$$

where

$$55 \quad K = \frac{1}{2} \log \left\{ \frac{Z_0'}{Z_0''} \right\} \quad \text{or} \quad K = \frac{1}{2} \log \left\{ \frac{Z_0''}{Z_0'} \right\} \quad \text{whichever is positive}$$

60 K =a factor expressing the difference of impedance in successive sections of the impedance-matching device.

A simple calculation shows that the value of r for a one-half wave length line 11, 12 is from Equation 4 approximately equal to $2K$, whereas its value for a quarter-wave length line is approximately

$$\frac{K}{4}$$

70 From this, it will be apparent that a wider range of impedance matching is provided by longer lengths of the line 11, 12. It should be pointed out, however, that the longest useful length of line designed by these principles is one which

provides an effective electrical length not substantially exceeding one wave length of the translated electromagnetic-wave signal.

Fig. 3 illustrates a high-frequency impedance-matching device for matching one terminal impedance coupled to one end of the device to a pair of terminal impedances connected in parallel at the other end of the device. This device is generally similar to that shown in Fig. 1 and similar elements are designated by similar reference numerals. A second hollow outer conductor 27 is inserted through an aperture 36 in the hollow conductor 11 and is electrically connected at its mid-portion and in a symmetrical manner to the latter conductor with the axis of conductor 27 at right angles to the axis of conductor 11. At the extremities of hollow conductor 27 are a pair of insulating discs 28, 28 which support a second inner conductor 29 coaxially with the outer conductor 27 by means of a pair of centrally disposed conductive pins 30. One end of conductor 12 is similarly supported in the first hollow conductor 11 by another disc 28 and a conductive pin 30. The other end of conductor 12 is conductively connected to the mid-portion of conductor 28. Annular conductive members 31 are secured to the outer ends of hollow conductors 11 and 27 by means of screws 14 to form a rigid unit. The conductive pins 30 and the annular members 31 thus form coaxial connectors for coupling the impedance-matching device of Fig. 3 in circuit with the external impedances which are to be matched. A conductive disc 35 closes the end of the conductor 11 adjacent the conductor 27. Slot 40 provides access to members 15 and 16 for adjustment purposes as in the Fig. 1 arrangement.

By way of example, an impedance-matching device embodying the present invention has been constructed for operation at a frequency near 500 megacycles for matching a 50-ohm impedance Z_2 to a 25-ohm impedance Z_1 composed of two 50-ohm impedances each $2Z_1$ connected in parallel, the geometric mean of the terminal impedances thus being 35 ohms. This matching problem therefore involves an impedance ratio of 2 to 1. This device, when accurately adjusted at one operating frequency, has been found to maintain a close impedance match over a wide range of operating frequencies or band width of approximately one-third to one-half the mean frequency. The following dimensions are given as illustrative of values of the elements which were utilized in this impedance-matching device for the application stated above:

Hollow outer conductor 11:

Length	.....	inches	5 $\frac{1}{2}$
Inner diameter	.....	do	1 $\frac{1}{8}$

Hollow conductor 27:

Length	.....	do	2 $\frac{1}{4}$
Inner diameter	.....	do	3/4

Inner conductor 12:

Length	.....	do	5 $\frac{1}{8}$
Outer diameter	.....	do	1/2

Inner conductor 29:

Length	.....	do	1 $\frac{1}{8}$
Outer diameter	.....	do	5/8

Adjustable members 15 and 16:

Length	.....	do	1 $\frac{1}{8}$
Outer diameter	.....	do	7/8

Impedance Z_2'	.....	ohms	52
Impedance Z_2''	.....	do	18

Referring now to Fig. 4, there is illustrated on a hemispherical impedance chart a representative

calibration chart at a particular operating frequency for an impedance-matching device embodying the present invention and having its dimensions so chosen that the line 11, 12 has a length of one-quarter wave length and a characteristic impedance equal to $3Z_2$ while each of the members 15 and 16 has a length of one-sixteenth wave length and a characteristic impedance equal to $0.6Z_2$. A chart of this type is useful in determining the required settings of the adjustable members 15, 16 in a particular impedance-matching device. This chart is also useful as a graphical representation of the matching capabilities of such a device. In this chart, the magnitude of any given impedance is expressed as a ratio between the value of that impedance and a value of resistance arbitrarily assigned the unit center of the chart. Ratio values are indicated by the lines of latitude, ratio values greater than unity lying above the straight horizontal line while those less than unity fall below this line. The possible phase angles of the given impedance are represented by the lines of longitude. The lines of longitude to the right of the straight vertical line represent an inductive phase angle while those to the left indicate a capacitive phase angle.

The generally triangular figure of the chart represents the extreme impedance-matching capabilities of an impedance-matching device having the values of characteristic impedance mentioned in the preceding paragraph. The data from which this triangular figure was plotted was determined by calculation using standard transmission line theory. In this regard, it is convenient to derive a general equation for the impedance Z_2 seen at one end of the line when an impedance Z_1 is coupled to the other end of the line. In this general equation, there will be one term for each of the line sections A, B and C, Fig. 2, in which the impedance transformation effected by each section is expressed as a function of the length of the section. There will also be one term expressing the impedance transformation effected by the line sections which include the members 15 and 16, but each of these terms will involve no variables since the characteristic impedance and the length of each such section have fixed values. In performing these computations, it is convenient to assign for a given set of computations a fixed value to one of the spacings A or B and then to compute values of impedance transformation effected by the impedance-matching device for selected values of the other spacing A or B. To plot the data thus obtained by calculation, an arbitrary value of resistance is assigned to the unit center of the impedance chart, as earlier explained. For the triangular figure shown on the impedance chart of Fig. 4, it was assumed that the impedance Z_2 was resistive and was equal to the value assigned to the center of the impedance chart. Z_2 may, for example, correspond to a resistance having a value of 50 ohms.

It will be noted that the triangular figure shown on the impedance chart is subdivided by a series of curves A and curves B which correspond to various possible A and B spacings, expressed in electrical degrees, of the adjustable members 15 and 16. A and B spacings here referred to correspond to those indicated in Fig. 2. The plotted data determined by calculation for three values of dimension A for 0, 15 and 30 electrical degrees are plotted on the impedance chart and the resultant curves are indicated as

$A=0^\circ$, $A=15^\circ$, and $A=30^\circ$ respectively. The $A=0^\circ$ curve, for example, represents the values of impedance transformation effected by the impedance-matching device with variations of the spacing B for a fixed spacing of zero electrical degrees for dimension A . Similarly, the curve $A=15^\circ$ represents the values of impedance transformation with variation of the dimension B when the dimension A has a fixed value of 15° electrical degrees. Since the lengths of the members 15 and 16 each correspond to 22.5 electrical degrees, there can only be one value of impedance transformation for the value of dimension A equal to 45° , since in this case the members 15 and 16 must then be positioned at the extreme opposite ends of the impedance-matching device. This value of impedance transformation is indicated by the point denoted $A=45^\circ$ as shown in the upper left of the figure. The triangular figure is also subdivided by three B curves indicated as $B=0^\circ$, $B=15^\circ$, and $B=30^\circ$ which represent the values of impedance transformation effected by the device for selected fixed values of the B spacing but with varying values of the A spacing. For a B spacing equal to 45° , the members 15 and 16 are in abutting relation and positioned at one end of the transmission line 11, 12 so that there can only be one value of impedance transformation, this value being indicated by the point $B=45^\circ$ shown at the lower left of the figure.

In using a chart of the type shown in Fig. 4 to determine the required spacing of the adjustable members 15, 16, assume that it is desired that the impedance-matching device transform an impedance Z_1 having a value indicated by the point P on the impedance chart to the value of impedance Z_2 , whereby the impedances Z_1 and Z_2 are matched by the device. This point P lies on the intersection of the curves $A=15^\circ$ and $B=0^\circ$. Hence, if the member 15 is adjusted to the end of the transmission line 11, 12 which reduces the B spacing to zero and if the adjustable member 16 is then adjusted to make the A spacing equal to 15 electrical degrees, an impedance Z_1 having the value represented by the point P on the impedance chart is transformed to the value of impedance Z_2 at the opposite end of the transmission line, or conversely the impedance Z_2 is transformed by the impedance-matching device to a value of impedance represented by the point P on the impedance chart. As a second example, assume that an impedance Z_1 having the value represented by the point P' on the impedance chart is to be matched by the impedance-matching device to an impedance having the value Z_2 . As indicated by the intersection of the broken lines which represent only portions of A and B curves, an impedance match is effected when the spacing B has a value of approximately $7\frac{1}{2}$ electrical degrees and the spacing A a value of approximately $7\frac{1}{2}$ electrical degrees.

While members 15 and 16 have been illustrated as closed or solid conductors slideable on the inner conductor, these members may have any of the configurations and mountings of, and may be formed in similar manner as, the adjustable members shown and described in the aforementioned copending applications. Thus the members 15 and 16 may be entirely of conductive, magnetic, or dielectric materials or may be formed of two or more of these materials in combination to provide an impedance-matching device having a particular desired characteristic. For high-voltage applications, it may prove desirable to round the ends or corners of the mem-

bers 15 and 16 where the latter are of conductive or magnetic materials. Further, while the invention has been described in connection with a coaxial impedance-matching device, it will be apparent to one skilled in the art that the invention is also useful with open-pair or balanced transmission lines having adjustable members of configuration, construction and mounting similar to those shown and described in the aforementioned copending applications.

It will be apparent from the foregoing description of the invention that a high-frequency impedance-matching device embodying the invention is of minimum physical size, is not critical of adjustment, and is not critical with regard to frequency or, expressed in another manner, is able to provide an exact impedance match at a selected operating frequency and a closely approximate impedance match over a wide range of operating frequencies.

While there have been described what are at present considered to be the preferred embodiments of this invention, it will be obvious to those skilled in the art that various changes and modifications may be made therein without departing from the invention, and it is, therefore, aimed to cover all such changes and modifications as fall within the true spirit and scope of the invention.

What is claimed is:

1. A high-frequency impedance-matching device adapted for connection between and for matching at a given frequency a pair of impedances having any values within a predetermined range of magnitude and phase comprising, a plural-conductor transmission line adapted to be connected between said impedances and having a predetermined electrical length less than one wave length at said given frequency and a predetermined characteristic impedance differing in one sense from the geometric mean of said impedances, and a plurality of members positioned between the conductors of said line and independently adjustably movable axially therealong, each of said adjustable members having at said given frequency a predetermined effective electrical length substantially less than one-half the length of said line and having its shape and material so selected as to cause the characteristic impedance of said line over the lengths of said members to differ from said geometric mean of said impedances in the opposite sense from the sense in which said line differs therefrom and by such magnitude as to enable said transmission line for an adjusted position of said members to match the resistance components and to cancel the reactance components of said pair of impedances.

2. A high-frequency impedance-matching device adapted for connection between and for matching at a given frequency a pair of impedances having any values within a predetermined range of magnitude and phase comprising, a plural-conductor transmission line adapted to be connected between said impedances and having a predetermined electrical length less than one wave length at said given frequency and a predetermined characteristic impedance differing in one sense from the geometric mean of said impedances, and a plurality of members positioned between the conductors of said line and independently adjustably movable axially therealong, each of said adjustable members having at said given frequency a predetermined effective electrical length substantially less than one-half the

length of said line and having its shape and material so selected as to cause the characteristic impedance of said line over the lengths of said members to differ from said geometric mean of said impedances by approximately the same amount as that of said line but in the opposite sense from the sense in which said line differs therefrom to enable said transmission line for an adjusted position of said members to match the resistance components and to cancel the reactance components of said pair of impedances.

3. A high-frequency impedance-matching device adapted for connection between and for matching at a given frequency a pair of impedances having any values within a predetermined range of magnitude and phase comprising, a plural-conductor transmission line adapted to be connected between said impedances and having a predetermined electrical length less than one wave length at said given frequency and a predetermined characteristic impedance greater than the geometric mean of said impedances, and a plurality of members positioned between the conductors of said line and independently adjustably movable axially therealong, each of said adjustable members having at said given frequency a predetermined effective electrical length substantially less than one-half the length of said line and having its shape and material so selected as to cause the characteristic impedance of said line over the lengths of said members to be less than said geometric mean of said impedances by such magnitude as to enable said transmission line for an adjusted position of said members to match the resistance components and to cancel the reactance components of said pair of impedances.

4. A high-frequency impedance-matching device adapted for connection between and for matching at a given frequency a pair of impedances having any values within a predetermined range of magnitude and phase comprising, a plural-conductor transmission line adapted to be connected between said impedances and having a predetermined electrical length less than one wave length at said given frequency and a predetermined characteristic impedance greater than the geometric mean of said impedances, and a plurality of conductive members positioned between the conductors of said line but spaced from at least one conductor thereof and independently adjustably movable axially therealong, each of said adjustable members having at said given frequency a predetermined effective electrical length substantially less than one-half the length of said line and having its shape so selected as to cause the characteristic impedance of said line over the lengths of said members to be less than said geometric mean of said impedances by such magnitude as to enable said transmission line for an adjusted position of said members to match the resistance components and to cancel the reactance components of said pair of impedances.

5. A high-frequency impedance-matching device adapted for connection between and for matching at a given frequency a pair of impedances having any values within a predetermined range of magnitude and phase comprising, a plural-conductor transmission line adapted to be connected between said impedances and having a predetermined electrical length less than one wave length at said given frequency and a predetermined characteristic impedance greater than the geometric mean of said impedances, and

a plurality of members of dielectric material positioned between the conductors of said line and independently adjustably movable axially therealong, each of said adjustable members having at said given frequency a predetermined effective electrical length substantially less than one-half the length of said line and having its shape so selected as to cause the characteristic impedance of said line over the lengths of said members to be less than said geometric mean of said impedances by such magnitude as to enable said transmission line for an adjusted position of said members to match the resistance components and to cancel the reactance components of said pair of impedances.

6. A high-frequency impedance-matching device adapted for connection between and for matching at a given frequency a pair of impedances having any values within a predetermined range of magnitude and phase comprising, a plural-conductor transmission line adapted to be connected between said impedances and having a predetermined electrical length less than one wave length at said given frequency and a predetermined characteristic impedance less than the geometric mean of said impedances, and a plurality of members positioned between the conductors of said line and independently adjustably movable axially therealong, each of said adjustable members having at said given frequency a predetermined effective electrical length substantially less than one-half the length of said line and having its shape and material so selected as to cause the characteristic impedance of said line over the lengths of said members to be greater than said geometric mean of said impedances by such magnitude as to enable said transmission line for an adjusted position of said members to match the resistance components and to cancel the reactance components of said pair of impedances.

7. A high-frequency impedance-matching device adapted for connection between and for matching at a given frequency a pair of impedances having any values within a predetermined range of magnitude and phase comprising, a plural-conductor transmission line adapted to be connected between said impedances and having a predetermined electrical length less than one wave length at said given frequency and a predetermined characteristic impedance less than the geometric mean of said impedances, and a plurality of members of magnetic material positioned between the conductors of said line and independently adjustably movable axially therealong, each of said adjustable members having at said given frequency a predetermined effective electrical length substantially less than one-half the length of said line and having its shape so selected as to cause the characteristic impedance of said line over the lengths of said members to be greater than said geometric mean of said impedances by such magnitude as to enable said transmission line for an adjusted position of said members to match the resistance components and to cancel the reactance components of said pair of impedances.

8. A high-frequency impedance-matching device adapted for connection between and for matching at a given frequency a pair of impedances having any values within a predetermined range of magnitude and phase comprising, a coaxial transmission line adapted to be connected between said impedances and having a predetermined electrical length less

than one wave length at said given frequency and a predetermined characteristic impedance differing in one sense from the geometric mean of said impedances, and a plurality of members positioned within said line between the conductors thereof and independently adjustably movable axially along said line, each of said adjustable members having at said given frequency a predetermined effective electrical length substantially less than one-half the length of said line and having its shape and material so selected as to cause the characteristic impedance of said line over the lengths of said members to differ from said geometric mean of said impedances in the opposite sense from the sense in which said line differs therefrom and by such magnitude as to enable said transmission line for an adjusted position of said members to match the resistance components and to cancel the reactance components of said pair of impedances.

9. A high-frequency impedance-matching device adapted for connection between and for matching at a given frequency a pair of impedances having any values within a predetermined range of magnitude and phase comprising, a coaxial transmission line adapted to be connected between said impedances and having a predetermined electrical length less than one wave length at said given frequency and a predetermined characteristic impedance differing in one sense from the geometric mean of said impedances, and a plurality of members each enclosing the inner conductor of said line and independently adjustably movable axially along said line, each of said adjustable members having at said given frequency a predetermined effective electrical length substantially less than one-half the length of said line and having its shape and material so selected as to cause the characteristic impedance of said line over the lengths of said members to differ from said geometric mean of said impedances in the opposite sense from the sense in which said line differs therefrom and by such magnitude as to enable said transmission line for an adjusted position of said members to match the resistance components and to cancel the reactance components of said pair of impedances.

10. A high-frequency impedance-matching device adapted for connection between and for matching at a given frequency a pair of impedances having any values within a predetermined range of magnitude and phase comprising, a plu-

ral-conductor transmission line adapted to be connected between said impedances and having an electrical length of approximately one-quarter wave length at said given frequency and a predetermined characteristic impedance differing in one sense from the geometric mean of said impedances, and a plurality of members positioned between the conductors of said line and independently adjustably movable axially therealong, each of adjustable members having at said given frequency an effective electrical length of approximately one-sixteenth wave length and having its shape and material so selected as to cause the characteristic impedance of said line over the lengths of said members to differ from said geometric mean of said impedances in the opposite sense from the sense in which said line differs therefrom and by such magnitude as to enable said transmission line for an adjusted position of said members to match the resistance components and to cancel the reactance components of said pair of impedances.

11. A high-frequency impedance-matching device adapted for connection between and for matching at a given frequency a pair of impedances having any values within a predetermined range of magnitude and phase comprising, a plural-conductor transmission line adapted to be connected between said impedances and having an electrical length of approximately one-quarter wave length at said given frequency and a predetermined characteristic impedance differing in one sense from the geometric mean of said impedances, and a plurality of members positioned between the conductors of said line and independently adjustably movable axially therealong, each of said adjustable members having at said given frequency an effective electrical length of approximately one-sixteenth wave length and having its shape and material so selected as to cause the characteristic impedance of said line over the lengths of said members to differ from said geometric mean of said impedances by approximately the same amount as that of said line but in the opposite sense from the sense in which said line differs therefrom to enable said transmission line for an adjusted position of said members to match the resistance components and to cancel the reactance components of said pair of impedances.

HAROLD A. WHEELER.
